UNITED STATES PATENT OFFICE

EDWIN T. DEAL, OF ALDAN, AND LOUIS F. SCOTT, OF PHILADELPHIA, PENNSYLVANIA, ASSIGNORS TO THE J. G. BRILL COMPANY, OF PHILADELPHIA, PENNSYLVANIA, A CORPORATION OF PENNSYLVANIA

DESIGN FOR A CHAIR

Application filed October 1, 1929. Serial No. 32,909. Term of patent 7 years.

To all whom it may concern:

Be it known that we, EDWIN T. DEAL and LOUIS F. SCOTT, citizens of the United States, residing, respectively, in Aldan, Pennsylvania, and Philadelphia, Pennsylvania, have invented a new, original, and ornamental Design for a Chair, of which the following is a specification, reference being had to the accompanying drawing, forming part thereof, in which the figure is a perspective view of a chair showing our new design.

We claim:—

The ornamental design for a chair, substantially as shown.

EDWIN T. DEAL.
LOUIS F. SCOTT.
